UNITED STATES PATENT OFFICE.

ORR T. NICHOL, OF OMAHA, NEBRASKA, ASSIGNOR OF ONE-HALF TO ALBERT H. BECKER, OF COUNCIL BLUFFS, IOWA.

GOVERNOR FOR TRACTOR ENGINES.

Application filed January 3, 1927. Serial No. 158,599.

My invention relates to governors for internal combustion engines, and particularly to governing mechanism attachable to such engines as accessory equipment therefor. It is the object of my invention to provide a governor mechanism especially adapted for use upon the well-known Fordson tractor, which may be readily attached thereto without requiring alteration of any of the standard parts of the tractor engine, and which will provide an efficient, durable and economical means for automatically controlling the speed of the engine.

A structure embodying my invention is illustrated in the accompanying drawings, in which Fig. 1 is a vertical section through the front cover extension of the tractor engine, showing the governor mechanism in front elevation, the section being on the line 1—1 of Fig. 2, Fig. 2 is a side view of the front portion of the engine, showing the governor mechanism in place thereon, Fig. 3 is a detail section through the governor on the line 3—3 of Fig. 1, Fig. 4 is a partial front view and partial section on the line 4—4 of Fig. 3, Fig. 5 is a detail section on the line 5—5 of Fig. 4, and Fig. 6 is a section on the line 6—6 of Fig. 5.

In many instances, and particularly when devices are to be driven which require a substantially constant speed under varying loads, it is highly desirable to apply automatic speed-governing mechanism to the motor, or engine, of a Fordson tractor, but the application of such governor mechanism presents peculiar difficulties because of the relative inaccessibility of parts, to which the governor may be connected for driving the same, and also because of the limited space available in which the governor may be disposed without interfering with the standard parts of the motor and its adjuncts. In carrying out my invention I provide a governor mechanism for which the driving connection is formed at the front end of the motor cam-shaft, and accommodate such driving mechanism by a slight re-arrangement of the commutator of the ignition mechanism, which is normally connected with said portion of the cam-shaft.

In the normal construction and arrangement of the Fordson motor the cam-shaft 10 projects through an opening 11 in the front cover 12 of the cylinder-block 13, the end of said shaft having a threaded portion 14 on

which is disposed a nut 15 for retaining upon the shaft a collar which carries the commutator-brush, and there being in the cam-shaft adjacent to said threaded portion 14 a transverse pin 16 of which the protruding end is engaged with the brush-collar to prevent rotation of said collar relative to the shaft. In the face of the front cover 12, concentric with the cam-shaft 10, is a shallow cylindrical recess or seat 17 for receiving the open end of the commutator-case 18, the latter being held rotatively in said seat by means of a flat retaining-spring 19, the end of said spring resting in a depression in the front end of the case, and the spring being held by one of the front-cover-bolts 20. A trough-like extension 21 is formed integrally with and projects forwardly from the lower portion of the front cover 12, said extension having on the bottom thereof lugs 22 for connection with the front axle of the tractor, and the radiator 23 being supported upon the upper front portion of said extension. The fan-drive pulley 24 is mounted upon the front end of the crank-shaft 25 within the lower portion of the trough-member 21, and from said pulley the fan-belt 26 extends up to the fan-pulley 27, the fan 28 being disposed between said pulley and the rear side of the radiator 23, and the fan-shaft being carried upon a bracket 29 extending down from the radiator-top-tank-connection 30. The parts hereinbefore designated by reference numerals are shown in Figs. 1, 2 and 3, and constitute the structural environment of my governor mechanism, all of said parts having the usual or standard structure and arrangement, except the commutator devices, as hereinafter explained.

In applying my governor mechanism, the commutator-case 18 is removed from the seat 17, the commutator-brush is removed from the cam-shaft, and the collar, usually employed for connecting the brush with the cam-shaft, is discarded. The casing 31 of the governor fits against the front cover 12, and a circular boss 32 is provided upon the rear side of said casing, said boss fitting into the seat 17 so that an opening 33 in the casing is aligned with the opening 11 about the cam-shaft 10, as shown in Fig. 3. At the upper part of the governor-casing 31 is a lug 34 having an opening which registers with one of the holes for the front-cover-bolts. For this hole a special bolt 35 is provided which is longer

than the ordinary bolt, and said special bolt serves to retain the governor-casing in place, while the casing is accurately positioned by the engagement of the boss 32 in the seat 17. 5 The front of the casing 31 is closed by a plate 36 secured removably thereon by screws 37, and said plate 36 has formed integrally therewith the cylindrical housing 38 which extends forwardly therefrom between the pulleys 24 and 27, so as to be straddled by the fan-belt 26 as shown in Fig. 1. The front end of the housing 38 has a cover-plate 39 removably secured thereon by screws 40. Within the casing 31 is a gear 41 which is disposed concentrically with the cam-shaft 10, the hub of said gear fitting slidably upon the cam-shaft, and the bore of the hub having a keyway 42 therein, into which the end of the pin 16 extends to form a driving connection between the shaft and gear. The nut 15 on the threaded end of the cam-shaft holds the gear in place longitudinally, and the rearwardly extending portion of the gear-hub fits into the opening 33 in the rear side of the casing. The front side of the gear 41 is cupped or annularly recessed, and the front plate 36 of the casing has a cup or cylindrical inwardly extending portion 43 which fits within the cupped face of the gear as best shown in Fig. 3. The cup, or portion 43 of the casing, has an opening therein concentric with the cam-shaft, and adjacent to the edges of said opening is formed a seat 44, similar to the seat 17, for receiving the rear end of the commutator-case 18. The latter, being placed in said seat 44, is retained therein by the spring 19 in the same manner as when disposed in the seat 17, and is in substantially its usual relation to the cam-shaft, being merely shifted forwardly or longitudinally of the cam-shaft a distance equal to that between the seats 17 and 44. The commutator-brush-assembly, comprising the roller 45, lever 46 and spring 47, is mounted upon the front hub of the gear 41 as best shown in Fig. 4, so that the brush is in proper operative relation to the commutator when the case 18 is engaged in the seat 44. 50 A gear 48 is disposed in the casing 31, said gear being positioned concentrically with the housing 38, and meshing with the gear 41 so as to be driven thereby. A shaft 49 is fixedly connected or integrally united with said gear 48, and extends therefrom forwardly through the housing 38, the front end of said shaft being shouldered to receive the inner race 50 of a ball bearing 51, and the outer race 52 of said bearing being seated in a recess in the cover-plate 39 of the housing. The rear side of the gear 48 is recessed to receive a ball bearing 53 of which the outer race 54 is pressed into the recess of the gear, and the inner race 55 is supported upon a fixed post 56 which extends forwardly from the back-

plate of the casing 31. On the front side of the gear 48 is a pair of lugs 57 which are diametrically opposite, and upon which are pivoted the fly-weights 58, each of said weights having at the rear end thereof a 70 pair of lugs which straddle the respective lug 57 to receive the pivot-pin 59. From one of the pivot-lugs on each weight an arm 60 is extended inwardly alongside the shaft 49, as best shown in Fig. 6. The inner or adjacent sides of the weights 58 are concaved to fit about a spool-shaped collar 61 which is mounted slidably upon the shaft 49, the rear end of said collar adjoining the arms 60, so that when the weights move outwardly said arms 60 push the collar forwardly as shown in Fig. 5. A ball thrust-bearing 62 is disposed about the shaft adjoining the front end of the collar 61, and in front of said bearing is the disc 63. In the upper part of the housing 38 is pivotally supported a transverse rocking-shaft 64 to which is secured an arm 65 having a forked lower portion which extends down in front of the disc 63, straddling the shaft 49, as shown. A portion of the rocking-shaft 64 projects laterally from the housing and has a U-bend 66 formed therein, the outer leg of the U-bend being returned to the normal axis, and the shaft then continued to a crank-arm 67 which extends upwardly and rearwardly from the shaft-axis. A rod 68 is connected with the upper end of the crank-arm 67 by means of a ball-joint 69, and said rod 68 is extended to and connected with the engine-throttle in any suitable manner, such that the throttle-opening will be increased and decreased by movement of the rod 68 forwardly and rearwardly, respectively. 90

The operation of the described governor mechanism will be readily apparent. The gear 41, being larger than the gear 48, will drive the latter at a higher speed than that of the cam-shaft 10 on which the drive-gear is mounted. The weights 58, mounted directly on the gear 48, are thrown outwardly by the centrifugal force resulting from their rotation with the gear, the motion of the weights is communicated through the arms 60, collar 61, thrust-bearing and disc 63, to the forked arm 65 of the rocking-shaft, and the latter is thereby actuated to operate the engine-throttle. 105

It will be noted that the mechanism consists of few and simple parts, and may be inexpensively produced by reason of such simplicity of structure. The disposal of the rear bearing for the shaft 49 within the recessed rear side of the gear 48 enables said gear and the gear 41 to be placed directly against the rear plate of the casing, so that the over-all thickness of the casing may be merely the thickness of the gears plus that of the back-plate and cover of the casing. The flat formation of the casing 110

enables the same to be disposed against the front-cover of the engine, in the limited space behind the fan-belt and fan-pulleys, while the projecting housing 38, inclosing 5 the fly-weights, may extend into the space between the straight portions of the fan-belt intermediate the fan-pulleys 24 and 27. The compact arrangement attained by the 10 cupping of the drive-gear 41 and of the front-plate of the casing, enables the placing of the commutator mechanism so nearly in the usual position thereof as to require no extension of the cam-shaft, or alteration of the retaining spring 19 or of the commutator 15 control-rod, while allowing a thickness at the toothed rims of the gears sufficient to afford ample strength and wearing capacity thereof. The U-bend 66 of the rocking-shaft allows the same to pass around the fan-belt, 20 so as not to interfere therewith, while allowing the necessary rocking movements of the shaft. The opening 33 of the governor-casing, being in register with the opening 11 through the front-cover, and said opening 25 11 communicating with the interior of the crank-case, a sufficient quantity of oil is received through said openings, by plashing from the crank-case, to efficiently lubricate the governor mechanism without the provision of other means of lubrication therefor.

Now, having described my invention, what I claim and desire to secure by Letters Patent is:

- 35 1. In a governor mechanism for Fordson tractor engines, a cupped gear adapted to fit upon the engine cam-shaft in the normal location of the commutator-brush-assembly, a commutator-brush mounted upon said gear at the cupped front side thereof, a governor-casing inclosing said gear and having a cupped front portion extending into the cupped side of the gear, said portion of the casing having an opening therein through 40 45 which the gear-hub and commutator-brush extend, there being formed in the casing about said opening a seat for retaining a commutator-case in operative relation with
- 50 said commutator-brush, and means for securing said casing upon the front-cover of the engine.
2. In a structure as set forth in claim 1, a boss formed on the rear side of said governor-casing and adapted to fit within the commutator-case-seat in the front-cover of the engine.
  3. A structure as set forth in claim 1, in which the means for securing the governor-casing upon the front-cover comprise a boss formed on the rear side of said casing and 60 extending into the commutator-case-seat of the front-cover, a lug on the casing having an opening registering with one of the front-cover bolt-holes, and a front-cover-bolt 65 extending through said lug.
  4. In a governor mechanism for Fordson tractor engines, a relatively thin flat casing disposed against the front-cover of the engine behind the fan-belt thereof, a housing member on the front of said casing and 70 extending into the space between the vertical portions of the fan-belt, a longitudinal shaft journaled in said housing member, a gear secured to the rear end of said shaft and extending peripherally into the flat casing, fly-weights connected with said gear 75 and extending about said shaft within said housing member, the rear side of said gear being centrally recessed, bearing means disposed in said recess and supported upon the rear portion of the flat casing, and a drive-gear disposed within the flat casing and meshing with said first-named gear, said drive-gear being secured upon the portion of the engine cam-shaft which projects 80 through the front-cover.
  5. A structure as set forth in claim 4, including a transverse rocking-shaft actuatable by the fly-weights and extending laterally from the housing member, said rocking-shaft having a U-bend straddling the adjacent portion of the fan-belt, and a crank-arm formed at the extremity of said shaft 85 outside the U-bend.

ORR T. NICHOL.
